UNITED STATES PATENT OFFICE.

ANDREW J. BROOKINS, OF CHICAGO, ILLINOIS.

TRAIN-CONTROL APPARATUS.

1,389,094.

Specification of Letters Patent.

Patented Aug. 30, 1921.

Application filed June 10, 1920. Serial No. 387,847.

To all whom it may concern:

Be it known that I, ANDREW J. BROOKINS, a citizen of the United States, and a resident of Chicago, in the county of Cook and State 5 of Illinois, have invented certain new and useful Improvements in Train-Control Apparatus, of which the following, when taken in connection with the drawings accompanying and forming a part hereof, is a full and 10 complete specification.

This invention relates to block signal railway systems wherein clear, caution, and danger signals are exhibited in the cabs or motors equipped with apparatus co-acting 15 and co-operating with track and track side installations, said signals corresponding with and indicating the condition of said track and track side installations.

Among the objects of the invention are 20 to obtain new and novel means to exhibit, in a moving cab or motor traveling on a railway track which is equipped with a block signal system, the conditions of the track and track side installations in a plurality of 25 blocks in advance of said moving cab or motor, said conditions being responsive to the conditions, whether occupied or unoccupied, of the track rails in said blocks; to obtain a cab or motor carried apparatus re- 30 sponsive to the conditions, whether normal or abnormal, and whether automatically or manually created, of track or track side installations of blocks in advance of said moving cab or motor. Additional objects are to 35 obtain a cab or motor carried apparatus, of the kind recited, which consists of few parts, not liable to become broken, or to get out of order, which will operate with certainty and accurately exhibit the existing conditions of 40 the track and track side installations, which is understandable by men skilled in the art of railroading, which is economically made and durable, and which will exhibit the three conditions known as clear, caution, 45 and danger.

In the drawings referred to I have illustrated a plurality of blocks of a track way provided with a block signal system comprising track and track side installations 50 adapted to co-act with the cab or motor carried apparatus which is illustrated, and in said drawings—

Figure 1 is a side elevation of a track rail, a ramp rail, and a diagram of trucks on said 55 rail and an apparatus embodying the cab or

motor carried apparatus mounted on the truck.

Fig. 2 is a diagram of track rails, a ramp rail, cabs or motors on said rails, and track and track side installations controlled by 60 track conditions, (whether occupied or unoccupied).

Fig. 3 is a top plan view of an apparatus embodying the cab or motor carried construction embodying the invention, the upper portion of the shell or case being removed to expose the operable parts to view. 65

Fig. 4 is a vertical section on line 4—4 of Fig. 3, viewed as indicated by arrows, with the parts which are in elevation in the same 70 position as in said Fig. 3.

Fig. 5 is an elevation of the operable parts of said apparatus, and of a portion of a ramp rail, a part of the case of the apparatus being removed and a part in cross section. 75

Fig. 6 is an end elevation, on line 6—6 of Fig. 5, viewed as indicated by arrows and in similar position as in said Fig. 5.

Fig. 7 is an elevation of the operable parts 80 which are illustrated in Fig. 5, in a different position from that illustrated in said Fig. 5.

Fig. 8 is an end elevation, on line 8—8 of Fig. 7, viewed as indicated by arrows and in similar position as in said Fig. 7. 85

Fig. 9 is an elevation of the operable parts which are illustrated in Figs. 5 to 8, inclusive, said parts being in an additional different position, and

Fig. 10 is an end elevation, on line 10—10 90 of Fig. 9, and in similar position as in said Fig. 9.

Fig. 11 is a diagrammatic view showing the relative position of the permanent magnet and electro-magnet. 95

A reference character applied to designate a given part indicates said part throughout the several figures of the drawing, wherever the same appears.

Referring to Figs. 1 and 2, the numerals 1, 100 2, 3 and 4 represent insulated blocks of a railway system, and in Fig. 2 the several parts and members illustrated are shown in diagram. X, X¹, (Fig. 2), represent motors or cabs positioned in blocks 1 and 4, respectively, motor X being assumed to be the moving one, and to be traveling in the direction toward motor X¹. Of the track and track side installations which are indicated in Fig. 2, those which are in blocks 2 and 3 105 110

are controlled by motor X^1 , in block 4, and are indicated in the positions automatically created thereby. The several elements and members which are indicated in Fig. 2, and 5 about to be described, are respectively provided with an index numeral which indicates the block in which they are installed, for instance, A^1 represents one rail of the track in block 1, A^2 , the same rail in block 10 2, A^3 said rail in block 3, and A^4 said rail in block 4. B^1 , B^2 , B^3 , and B^4 , respectively represent the other rail of the track, in blocks 1, 2, 3 and 4. C^2 , C^3 , and C^4 represent track relays in blocks 2, 3 and 4. D^2 , d^2 , 15 D^3 , d^3 , and D^4 , d^4 , represent electrical conductors which are respectively attached, at one end, to the relays C^2 , C^3 , and C^4 , and at the other end to rails A^2 , A^3 , A^4 , and B^2 , B^3 , and B^4 . E^1 , E^2 , E^3 , and E^4 , represent batteries, in blocks 1, 2, 3 and 4, respectively, 20 and e , e^1 , represent electrical conductors, which are attached to said batteries and to rails A and B, in the blocks in which said batteries are positioned. F^2 , F^3 , and F^4 , represent track side relays which are positioned in blocks 2, 3 and 4, respectively. G^1 , G^2 , G^3 , represent track side batteries, in blocks 1, 2, 3, and 4, respectively. H^1 , H^2 , H^3 and H^4 , represent electric conductors 25 which are respectively attached to one terminal of a relay of the F series and to a battery of the G series in the block indicated by the index numeral applied thereto. The track side relay in block 1, and the track side battery of block 4 are not illustrated, but the location and conductor connections thereto are similar to those in blocks 2 and 3, that is, conductor H^1 , from battery G^1 is attached to the relay of the F series in block 30 1, and the conductor H^4 in block 4 is attached to a battery of the G series, in said block 4. The positive poles of the batteries of the G series which are indicated by the characters G^1 , G^2 , and G^3 , are indicated by a plus sign, and the negative poles of said batteries are indicated by a minus sign. 35 h^1 , h^2 , and h^3 , represent electric conductors which, at one of the ends thereof, respectively, are attached to the coils of relays F^1 , F^2 , and F^3 , and at the other ends are branched into the conductors of the I series of the next block in advance. That is, h^1 is branched into conductor I^2 , h^2 into conductor I^3 , and h^3 into conductor I^4 . 40 55 J^2 , j^2 , J^3 , j^3 , J^4 , and j^4 , represent movable conductors which are controlled by relays C^2 , C^3 and C^4 , respectively, and K^2 , k^2 , K^3 , k^3 , K^4 , k^4 , respectively represent contact points co-actuable with the several movable conductors of the J and j series in the several blocks illustrated. 60 65 L^2 , L^3 and L^4 , respectively represent conductors which connect the positive poles of the batteries of the G series with the movable conductors of the J series in the several

blocks 2, 3 and 4, and l^2 , l^3 and l^4 represent conductors which are attached to the movable conductors of the j series and are branched into the conductors of the H series in blocks 2, 3 and 4; it being observed that 70 conductor l^2 is branched into conductor H^1 , conductor l^3 is branched into conductor H^2 , and conductor l^4 is branched into conductor H^3 .

M^2 , m^2 , M^3 , m^3 , and M^4 , m^4 represent movable conductors which are controlled by relays F^2 , F^3 , and F^4 , respectively. 75

N^2 , P^2 , N^3 , P^3 , N^4 , P^4 , represent contact points which are co-actuable with movable conductors M^2 , M^3 and M^4 , respectively, and n^2 , p^2 , n^3 , p^3 and n^4 , p^4 , represent contact points which are co-actuable with the movable conductors m^2 , m^3 , and m^4 , respectively. 80

O^2 represents a conductor which is attached to the descending side y^1 of the ramp 85 in block 1, and extends to contact points N^2 , p^2 , in block 2, being branched to extend to both said points. O^3 represents a conductor from descending side y^2 of the ramp in block 2 to contact points N^3 , p^3 in block 3, 90 said conductor being branched in the same manner as conductor O^2 . O^4 represents a conductor from descending side y^3 of the ramp in block 3 to contact points N^4 , p^4 , in block 4. 95

Q^2 represents a conductor from contact points P^2 and n^2 in block 2, (being branched as are the conductors of the O series as last above recited) to rail B^1 in block 1. Q^3 and Q^4 represent conductors similar to conductor Q^2 , which extend from contact points P^3 , n^3 , and P^4 , n^4 , to rails B^2 and B^3 , of blocks 2 and 3. 100

Z represents insulation between the ascending sections Y^1 , Y^2 , and Y^3 of the ramps in blocks 1, 2 and 3, and the descending sections y^1 , y^2 , y^3 , of said ramps, and between the rails A^1 , A^2 , A^3 , A^4 , and B^1 , B^2 , and B^4 . The several ramps are insulated in the usual manner. 110

Cab X^1 on the rails in block 4 shunts relay C^4 , the main portion or part of the current generated by the battery E^4 , flowing from said battery on one rail of the track to motor or cab X^1 through the wheels and axles of the cab to the other rail of the track and on said other rail to the battery. Relay C^4 not receiving sufficient current to energize it sufficiently to hold movable conductors J^4 , j^4 to contact points K^4 , k^4 , the track side installations of which said movable members are elements, will not be continuous. The track side installation starting from the positive pole of battery G^3 , and extending over conductors and contact points L^4 , J^4 , 120 K^4 , I^4 , M^4 , N^4 and O^4 to the descending section y^3 of the ramp (in block 3), is not continuous, because of being broken between movable conductor J^4 and contact point K^4 , 125 and said descending section will not be energized. 130

gized when the shoe of the cab or motor carried apparatus is in contact therewith. At the same time the relay F^3 , in block 3, is deenergized by the breaking of the continuity of contact between movable conductor J^4 and contact point K^4 , the conductor k^3 being branched into conductor I^4 , and extending from thence to relay F^3 , and by said conductor H^3 to the negative pole of battery or generator G^3 .

The relay F^3 being deenergized the movable conductors M^3, m^3 , will break contact with contact points N^3, n^3 , and make contact with contact points P^3, p^3 . A continuous track side installation from battery G^2 will thereby be obtained, which starting from the positive pole of battery G^2 , comprises conductor L^3 , movable conductor J^3 , contact point K^3 , conductor I^3 , movable conductor M^3 , contact point P^3 , conductor Q^3 to rail B^2 , and from descending section y^2 of said block 2, conductor O^3 , contact point p^3 , movable conductor m^3 , conductor i^3 , contact point k^3 , movable conductor j^3 , conductor l^3 and conductor H^2 , (conductor l^3 being branched into conductor H^2) to the negative pole of said battery G^2 .

The track installation of block 2 is not affected by the motor or cab X^1 on the rails in block 4, and hence, the relay C^2 is energized sufficiently to hold movable conductor J^2 in contact with contact point K^2 , and from battery G^1 there is a continuous track side installation from the positive pole of said battery to the descending section y^1 of the ramp, (in section 1), which includes $L^2, J^2, K^2, I^2, M^2, N^2$ and O^2 ; and from rail B^1 to the negative pole of said battery, which includes $Q^2, n^2, m^2, i^2, k^2, j^2, l^2$ and H^2 , (l^2 being branched into H^2).

It occurs, therefore, when the shoe of the motor or cab carried apparatus is brought into contact with the descending side or section y^1 , to co-act with the track side installation which controls said descending section, said section will be positively energized. When said shoe comes in contact with the descending section y^2 , said section will be negatively energized. And when said shoe comes in contact with the descending section y^3 it will not be energized.

In Figs. 3 to 10, inclusive, W represents the shell or case of the cab or motor carried apparatus about to be described.

R represents a lever which is fulcrumed at one end thereof on shaft r , and is provided at the other end with head R^1 . r^1 represents a slot in lever R , midway of the ends, and S^1 represents an abutment in said slot, said abutment being rigidly secured to plunger S so that movement of said plunger produces corresponding movement of head R^1 , and said lever is turned on its fulcrum: and the suspension of said lever in a determined position correspondingly suspends

said plunger. Head R^1 is provided with recesses, R^2, r^2 which are illustrated as on opposite sides thereof, and R^3, r^3 , represent pawls which are adapted to engage with said recesses, respectively, and when in engagement therewith to hold said lever in said determined positions, thereby suspending said plunger correspondingly. Pawls R^3, r^3 , are fulcrumed on abutments or pivots R^4, r^4 . R^5 represents a bar which is provided with an abutment or pin r^5 , said pin extending into slot r^6 in frame R^6 . R^7, r^7 , represent slots in bar R^5 , and R^8, r^8 , abutments or pins on pawls R^3, r^3 , which extend into said slots, thereby supporting said bar R^5 , and tying said pawls loosely together. R^9 represents an electromagnet, and r^9 the pole piece thereof. R^{10} represents a permanent magnet which forms the armature of electromagnet R^9 . Magnet R^{10} is secured on frame R^6 , as by screws r^{10}, r^{10} , and is pivotally mounted on pin R^{11} . Pin R^{11} forms the fulcrum on which frame R^6 and magnet R^{10} swings, said fulcrum being stationary, and illustrated in Fig. 3 as being mounted on ring r^{11} , which extends around the coil of electromagnet R^9 .

R^{12}, r^{12} , represent the poles of magnet R^{10} , which are indicated by plus and minus signs in Fig. 11, and the pole piece r^9 of electromagnet R^9 is extended to between said poles.

When the electromagnet R^9 is energized by current flowing through its coils, in one direction, the pole piece r^9 is excited and becomes a "north" pole or a "south" pole, depending on the direction of said flow; it will therefore attract the pole of permanent magnet R^{10} which is of opposite polarity, and repel the one of like polarity. This turns said magnet on its fulcrum in clockwise or counter clock-wise direction depending on the direction of said flow.

By this arrangement, longitudinal movement of bar R^5 a sufficient distance in one direction from the neutral position thereof, (illustrated in Fig. 6), will pivotally move pawls R^3, r^3 , (or one thereof), from said neutral position into the position illustrated in Fig. 8, and said sufficient movement of said bar in the opposite direction will pivotally move said pawls, (or one thereof), into the position illustrated in Fig. 10. At the same time, bar R^5 will be forced, relative to said pawls, into the position illustrated in Fig. 6, on the upward movement of head R^1 to its highest possible position by said head being forced between said pawls and forcing them into the position illustrated in Fig. 6, thereby returning the bar R^5 and frame R^6 to neutral position. Said pawls remaining in said neutral position, on the descent of the shoe T of the apparatus, the plunger S will descend therewith, and head R^1 be moved to the position indicated by broken

lines in Fig. 6. In case the descending section of the ramp is not energized when shoe T comes in contact therewith the permanent magnet and frame R⁶ do not move from said neutral position, and the head R¹ descends between the pawls R³, r³ on the descent of shoe T, the lever R turning on its fulcrum.

Plunger S is vertically movable in cylindrical chamber S², (formed by walls S⁶). S³, S⁴ represent stuffing boxes or glands. S⁵ represents a head which is rigidly secured in cylindrical walls S⁶. Gland S³ is represented as secured in head S⁵. S⁷ represents an air retaining cup, or piston ring, and S⁸ a nut on plunger S holding said cup or ring in place on plunger S. S⁹ represents an annular groove on plunger S which, when said plunger is in the position in which it is illustrated in Fig. 5, forms a by-pass around the plunger between passage way U and passage way u. U represents a passage way communicating at its inlet end with the train pipe of an air brake system and at its outlet end with the chamber S², and u, u¹, represent outlets from said chamber. Outlets u, u¹, may discharge to waste, to signals or to other devices, as desired, the utilization of the flow of air from said discharge not being included in this invention. Plunger S being in the position in which it is illustrated in Fig. 9, the flow of air therethrough is sufficient to make a light application of the brakes of the air brake system; and when said plunger is in the position illustrated in Fig. 4, the flow of air from inlet U, through the by-pass S⁹ and outlet is sufficient to make a heavy application of said brakes. The plunger is in the position indicating caution when said light application of the brakes is effected; and in danger when said heavy application is made. When head R¹ is in position indicating "clear," see Fig. 7, train pipe air pressure prevails in chamber S², plunger S is not in position however to permit a flow of air therethrough from inlet U to outlets u, u¹, or either of them, and no application of the brakes is automatically effected. The plunger S is, therefore, moved by the air under pressure in said chamber S², in an advance direction, when not arrested by one or the other of the pawls R³, r³, to "danger" position.

The shoe T is connected to links T¹, T¹, by pivots t, t, t¹, t¹, represent slots in links T¹, T¹, and T², T², represent pins in said slots. Pins T², T², are secured in abutments t², t², said abutments being integral with or rigidly secured to case W. Case W is insulated from the truck, motor or cab in which it is installed, as my insulating material Z¹, (Fig. 1), in the ordinary way, and W¹, Fig. 3, represents a conductor connecting case W to the coil of electromagnet R⁹, and W² a conductor from said coil

to the frame of the truck on which the apparatus is mounted.

When shoe T is in contact with the descending section of a ramp and the wheels of the motor or cab in which the apparatus is mounted are on a rail of the B series a closed electric circuit is formed, (the track side installations being continuous), the elements of said circuit which are in said apparatus comprising shoe T, links T¹, T¹, frame W, conductor W¹, the coil of electromagnet R⁹, conductor W², and the truck frame and wheels.

The plunger S, whether suspended or not by lever R as hereinbefore described, is in position to be engaged by shoe T, and as said shoe is brought into contact with the ascending section of a ramp it is raised, and upon said raising it engages and raises the plunger. As said shoe moves on to the descending section the non-suspension or suspension of the plunger by lever R, is determined by the non-energized or energized condition of said section, and the direction of the flow of current energizing it, said direction depending on the clear and caution condition of the track side installation, as hereinbefore described.

Electromagnet R⁹, being energized by a current flowing through the coil thereof in one direction, the armature R¹⁰ will be drawn or pulled in one direction by the pole piece r⁹, and upon said current flowing through said coil in the opposite direction said armature will be drawn or pulled in the opposite direction from its neutral position.

In case said descending section is energized as hereinbefore recited relative to section y¹, the electromagnet R⁹ will be energized to move its armature from the neutral position illustrated in Fig. 6 to the position illustrated in Fig. 8; pawl R³ will engage with recess R², and "clear" will be indicated. The circuit on which said current is assumed to flow comprises, from the positive pole of battery G¹, conductor L², movable conductor J², contact point K², conductor I², movable conductor M², contact point N², conductor O², descending section y¹ of the track side installation, shoe T, links T¹, T¹, shell W, conductor W¹, the coil of electromagnet R⁹, conductor W², and the frame of motor or truck X, of the cab carried apparatus, and rail B¹ of the track, and conductor Q², contact point n², movable conductor m², conductor i², contact point k², movable conductor j², conductor l², conductor H¹ to the negative pole of said battery G¹. It being observed that conductor l² is illustrated and described as branched into conductor H¹, and that the descending section y¹ is positively energized, as hereinbefore recited.

The above recited pull or draw of the

armature R^{10} will continue as head R^1 descends with the descent of plunger S , until the corresponding recess (R^2) is in position to permit said armature to move and move 5 bar R^5 and pawls R^3, r^3 , whereupon said armature will respond to said draw or pull and move frame R^6 , bar R^5 , and said pawls, moving pawl R^3 into engagement with recess R^2 .

- 10 Assuming the motor, cab or truck X to have traveled into block 2 and said descending section y^2 is energized as hereinbefore recited, the armature R^{10} will be drawn or pulled by the energizing of the electromagnet R^9 from the neutral position illustrated in Fig. 6 toward the position illustrated in Fig. 10, and said draw or pull will continue as head R^1 descends with the descent of plunger S , until the corresponding recess, (r^2), is in position to permit said armature to move, (moving bar R^5 and pawls R^3, r^3 , whereupon said pawl r^3 will enter said recess. Said lever R will at this time be in position indicating "caution," and the circuit which is closed and energized comprises, the positive pole of battery G^2 , in block 2, and the following elements, $L^3, J^3, K^3, I^3, M^3, P^3, Q^3$, of the track side installation, to rail B^2 , the wheels and frame of truck X , conductor W^2 the coils of electromagnet R^9 , conductor W^1 , case or shell W , links T^1, T^1 , and shoe T , of the cab carried members, (as before, but the current flowing in the opposite direction), and again of the track side installation of blocks 2, and 3, members $y^2, O^3, p^3, m^3, i^3, k^3, j^3, l^3$, and H^2 and the negative pole of said battery G^2 .

Assuming the motor, cab or truck X to have traveled into block 3, upon said shoe T coming into contact with descending section y^3 , (it being non-energized) said electromagnet R^9 will not be energized, and its armature will not be moved from the position thereof illustrated in Fig. 6, and said head R^1 , will descend from the position thereof there illustrated by full lines to the position indicated by broken lines, permitting plunger S to descend with the descent of shoe T , and "danger" will be indicated by said head R^1 .

The cab carried elements are identical in the last above recited conditions and the failure of the electromagnet R^9 from being energized is due to the fact that the continuity 55 of the track side installation is broken, the break occurring because movable conductors J^4, j^4 are not in contact with contact points K^4, k^4 , as herein before recited.

From the foregoing description and illustrations of the manner in which, upon the contact of the cab carried shoe with the descending section of a ramp rail the electromagnet R^9 is energized by a flow of electrical energy therethrough in opposite directions, 60 or whereby its energizing is not effected,

depending on the conditions of the track side installations; and the description and illustration of the manner in which the shoe of the cab carried apparatus is raised from its lowest to its highest position upon the contact of said shoe with the ascending section of said ramp; and the further explanation, that in whatever position the plunger may be by reason of its suspension or non-suspension by the latching mechanism of 70 the apparatus, said shoe, in its upward travel will move said plunger upward and destroy the condition created by the contact of said shoe with the last ramp contacted with and mechanically force said 80 latching mechanism into a neutral position, in readiness to be re-set by the co-action of the track side installation and the cab carried apparatus, as said shoe moves down the descending section of the ramp, the operation of the apparatus and the track side installations is believed to have been fully explained.

In the ramp illustrated and described the words "ascending" and "descending" imply, merely, that trains are moving in a direction to make such words applicable thereto; and if it be assumed that trains are moving in the opposite direction said words are applicable to the opposite sections, as 90 shown; and in illustrating and describing the train as moving in one direction, I do not thereby limit myself to a track side installation and co-acting motor or cab carried apparatus which is connected to one 100 section only of the several ramps; the limitation of the connection of conductors of the track side installation to one section of a two section ramp being simply for the sake of brevity and clearness in the illustrations 105 and description of the embodiment of the invention and its operation.

The chamber S^2 being, except for a brief moment when the shoe T passes over the apex of the ramp, in communication with the 110 air brake system of the train by means of passage way and chamber inlet U , the pressure in said chamber corresponds with the pressure of the train pipe of said system. It is the lessening of the pressure in said 115 chamber and a corresponding lessening of the pressure in the train pipe which causes this apparatus to control the application of brakes in said system. Further, said air pressure in said chamber S^2 , tends to advance plunger S , and when lever R and said plunger are suspended by one of the pawls R^3, r^3 , in engagement with a corresponding recess, said air pressure tending to advance 120 plunger S , thereby forces head R^1 down onto said pawl, thus preventing the jarring of said pawl out of engagement with said recess.

I claim:

1. In a block train control system, a track side installation in each of the blocks of said 130

system comprising a two-part ramp consisting of an insulated ascending and an insulated descending section and a conductor connected to said descending section, said 5 track side installations arranged to control the electrical condition of said descending section to correspond with the conditions, whether occupied or unoccupied of a determined number of blocks of said system, 10 in combination with a cab carried apparatus comprising a shoe, arranged to coact with said ramp, a plunger mechanically movable in a determined direction by the movement of said shoe in said direction, electro-responsive 15 means to suspend said plunger in a position corresponding with and indicating the electrical condition of said descending section.

2. In a block train control system, a track 20 side installation in each of the blocks of said system comprising a two part ramp consisting of an insulated ascending and an insulated descending section, and a conductor connected to said descending section, said 25 track side installation arranged to control the electrical condition of said descending section to correspond with the condition, whether occupied or unoccupied, of a determined number of blocks of said system, in 30 combination with a cab carried apparatus comprising a shoe arranged to coact with said ramp, a plunger mechanically movable in a determined direction by the movement of said shoe, electroresponsive means to suspend 35 said plunger in a position corresponding with and indicating the electrical condition of said descending section, said plunger arranged, on said mechanical movement thereof to release the means whereby existing 40 suspending means are maintained.

3. In a cab carried apparatus co-operable with a track side installation which is provided with a two part ramp, having an ascending and a descending section, and means 45 to control the electrical condition of said descending section, the combination of a movable shoe, a plunger and a lever connected to said plunger, electroresponsive means to arrest and maintain said lever in a determined 50 position, and mechanically operable means to release said arresting means, said shoe related to said ramp so as to be mechanically operated by the ascending section thereof and to be electrically responsive 55 to the descending section, and means to convey the electric condition of said shoe to said means to arrest.

4. In a block train control system, a track 60 side installation in each of the blocks of said system comprising a two part ramp having an ascending and a descending section, a conductor connected to said descending section, said track side installation arranged to control the electrical condition of said descending section to correspond to the condi- 65

tion, whether normal or abnormal, of a determined number of blocks in advance, in combination with a cab carried apparatus comprising a shoe arranged to coact with said ramp, a chamber, a communicating passage way between the air brake system of the cab and said chamber, an outlet from said chamber, a movable plunger in said chamber, adapted to be yieldingly forced in one direction, means responsive to the electrical condition of said descending section adapted to arrest the movement of said plunger in said direction in a selectively determined position, said plunger arranged to cut off communication between said chamber and said outlet when in one of said selectively determined positions, and to establish restricted communication between said chamber and said outlet when arrested in the remaining one of said selectively determined 85 positions.

5. In a block train control system, a track side installation in each of the blocks of said system comprising a two part ramp having an ascending and a descending section, a conductor connected to said descending section, said track side installation arranged to control the electrical condition of said descending section to correspond with the condition, whether normal or abnormal, 90 of a determined number of blocks of said system in advance of said descending section, in combination with a cab carried apparatus comprising a shoe, arranged to coact with said ramp, a plunger mechanically movable in a retracted direction by said shoe and yieldingly movable in an advance direction, electroresponsive means controlled by the electrical condition of said descending section to selectively position said 100 plunger.

6. In a block train control system, a track side installation in each of the blocks of said system comprising a two part ramp having an ascending and a descending section, in combination with a cab carried apparatus comprising a shell provided with a chamber, a communicating passage way between the air brake system of the cab and an outlet from said chamber, a shoe arranged to coact with said ramp, a plunger movable in said chamber and arranged to be yieldingly forced in an advance direction, means responsive to the energized electrical condition of said descending section to selectively arrest said plunger, and, said descending section not being energized, said yieldingly forcing means arranged to sufficiently advance said plunger to establish communication with said outlet from said 115 chamber.

7. In a train control system, a cab carried apparatus provided with a chamber, a communicating passage way between the air brake system of the cab and said chamber, 120

- and an outlet from said chamber, a plunger in said chamber said plunger adapted to be moved in one direction by the air in said chamber, means responsive to the flow of 5 an electric current in opposite directions to selectively arrest said movement of said plunger, said plunger arranged to close said outlet when arrested in one position and to establish restricted communication through 10 said outlet when arrested in another position.
8. In a train control system, a cab carried apparatus having as an element thereof a movable plunger and means to apply air 15 under pressure to said plunger to yieldingly force said plunger to an advanced position, a plurality of latch members adapted to respectively limit the advance movement of said plunger, in combination with a track 20 side installation arranged to mechanically retract said plunger, and means to selectively move said latch members into position to limit said advance movement of said plunger.
- 25 9. In a block train control system, a track side installation in each of the blocks of said system comprising a two part ramp having an ascending and a descending section, in combination with a cab carried apparatus 30 provided with a chamber and comprising a shoe arranged to co-act with said ramp, a plunger movable in said chamber, yielding means to move said plunger, means adapted to selectively arrest said movement of said 35 plunger, said ascending section, said shoe and said plunger co-acting to release and move said arresting means to inoperative position.
10. In a cab carried apparatus coöperable 40 with a track side ramp provided with an ascending and a descending section, a movable shoe arranged to co-act with said ascending section and electrically responsive to said descending section, a movable plunger operable to a retracted position by said shoe and to an advanced position by air under pressure, a lever, means to join said lever and plunger so that movement of said plunger moves said lever and the suspension 45 50 of said lever suspends said plunger, a plurality of means to arrest movement of said lever during the advance movement of said plunger, and means to selectively actuate said means to arrest.
- 55 11. A cab carried mechanism comprising a member adapted to be advanced by air under pressure, a lever connected to said member and provided with a plurality of engageable elements, means adapted to be advanced into 60 position engageable with said elements, in combination with an electroresponsive member arranged to selectively advance said last means into said engageable position.
12. A cab carried mechanism comprising
- a member adapted to be advanced by air 65 under pressure, a lever connected to said member and provided with a plurality of engageable elements, a plurality of members adapted to be advanced into engageable position with a corresponding one of said elements, in combination with an electroresponsive member arranged to selectively advance 70 said last members into said engageable position.
13. A cab carried mechanism comprising 75 a member adapted to be advanced by air under pressure, a lever connected to said member and provided with a plurality of engageable elements, a plurality of members adapted to be advanced into position engageable with a corresponding element, in combination with an electroresponsive member arranged to selectively advance said last members into engageable position, and mechanically actuatable means to retract said 80 85 plurality of members.
14. In a train control system, a track side installation comprising as elements thereof a source of electrical energy, a member electrically responsive to normal and abnormal 90 conditions of a plurality of adjacent blocks of said system, means to transmit electrical energy from said source to a cab carried member responsive to the direction of flow of said electrical energy, a plurality of latch 95 members, said cab carried responsive member arranged to selectively move said latch members to operable position.
15. In a train control system, a track side installation comprising as elements thereof 100 a source of electrical energy, a member electrically responsive to normal and abnormal conditions of a plurality of adjacent blocks of said system, means to transmit electrical energy from said source to a cab carried 105 member responsive to the direction of flow of said electrical energy, a plurality of latch members, said cab carried responsive member arranged to selectively move said latch members to operable position, and mechanically 110 operable means to move said latch members to inoperable position.
16. A cab carried mechanism comprising as elements thereof a member adapted to be yieldingly forced to an advanced position by 115 air under pressure, and a plurality of electroresponsive members adapted to selectively arrest advance movement of said first member, in combination with a track side installation comprising a member adapted to 120 mechanically move said arresting members to an inoperative position and to be selectively energized to move said electroresponsive members to operative position.
